UNITED STATES PATENT OFFICE.

GEORGE A. DOXEY, OF STATEN ISLAND, NEW YORK, ASSIGNOR TO MEGENTHALER LINOTYPE COMPANY, A CORPORATION OF NEW YORK

TYPOGRAPHICAL MACHINE.

Application filed March 2, 1927. Serial No. 171,927.

This invention relates to typographical machines, such as linotype machines of the general organization represented in U. S. Letters Patent to O. Mergenthaler No. 436,532, wherein circulating matrices are released from a channeled magazine in the order in which they are to appear in print and then assembled in line, the composed line transferred to the face of a mold, the mold filled with molten metal to form a slug or linotype against the matrices which produce the type characters thereon, and the matrices thereafter distributed according to character and returned through a channeled magazine entrance to the magazine from which they started.

In these machines, the magazine entrance is usually provided with a series of partitions which divide it into matrix channels and which are formed at their lower ends with bent-over flanges arranged to guide the matrices by their projecting ears as they pass to the magazine. In some instances, as when the entrance channels are extremely wide, these flanges are formed with auxiliary guiding elements or leaf sections which are fastened to the partitions and disposed at an inclination thereto so as to contract the channels toward their delivery ends, see Kennedy Patent No. 1,367,606. While such arrangement enables the entrance to handle matrices of varying thicknesses in many different fonts, its capacity is nevertheless limited. That is to say, the range in thickness of certain matrices of corresponding character in many fonts, particularly those used in setting advertising and display matter, is so great that some of the largest and smallest faces are excluded from use in the regular machines. It is the aim of the present invention to bring the capacity of the magazine entrance up to a point where it will be capable of handling all available display fonts irrespective of the difference in thickness of the corresponding matrix characters therein contained. To this end, means are provided whereby one or more of the aforesaid leaf sections, or their equivalents, may be adjusted individually and relatively to the partitions to vary the width of the respective channels as required. In the preferred

embodiment illustrated, these leaf sections are pivoted at their upper ends and at the lower ends are connected to a movable strip or plate which is operated automatically as a font is selected for use.

In the accompanying drawings, the invention is shown merely in preferred form and by way of example and as applied to a particular kind of linotype machine but obviously many changes and variations may be made therein and its application be extended to other types of machines without departure from its spirit. It should therefore be understood that the invention is not limited to any specific form or embodiment except in so far as such limitations are specified in the claims.

Referring to the drawings:

Fig. 1 is a side elevation partly in section 70 of a linotype machine showing the present invention applied thereto;

Fig. 2 is a longitudinal section upon an enlarged scale taken on the line 2—2 of Fig. 1;

Fig. 3 is a detail showing the form of the font distinguishing plates on the ends of the magazines;

Fig. 4 is a detail plan view of Fig. 3;

Fig. 5 is a vertical section taken on the 80 line 5—5 of Fig. 2;

Fig. 6 is a side elevation of the improved magazine entrance partly broken away to show one of the adjustable leaf sections; and

Fig. 7 is a detail perspective view of one 85 of the adjustable leaf sections and parts associated therewith.

In the course of distribution, the matrices X are advanced by the distributor screws A across the distributor bar A¹ from which 90 they drop according to character at different points therealong and enter appropriate channels of the magazine entrance B. Since the present improvements, as before intimated, are directed more particularly to the handling of display fonts, the magazine C herein illustrated is of the usual short or sectional type, being mounted on the base frame C¹ and used in connection with the intermediate guiding section C², which 95 conducts the matrices from the entrance B to the magazine. The entrance B (Fig. 2) is 100

divided into channels by the partitions B^1 which bear a fixed relation to one another and are spaced different distances apart to better accommodate the matrix fonts of maximum size or thickness. In adapting the channels to handle the matrices of thinner fonts, however, the partitions B^1 are provided with inclined guiding elements, or leaf sections B^2 , which are connected at their upper ends to the partitions B^1 and formed at their lower ends with bent-over flanges b for guiding the matrices by their projecting ears. Spacing blocks b^1 of varying thicknesses (while not essential) are preferably interposed between the lower ends of the leaf sections B^2 and the adjoining partitions to maintain the former at the inclination desired. The width of the channels are thus contracted in advance of the flanges b so that the thinner matrices in descending through the relatively wide channels will be straightened up and caused to enter the magazine in the proper position. So far as described, the parts are or may be the same as those presented in the Kennedy Patent No. 1,561,246, and in themselves constitute no part of the present invention.

At present, there are perhaps twelve or fifteen characters whose range in thickness in the different display fonts is so great that if the leaf sections B^2 be spaced far enough from the opposing partitions to allow the thickest matrices to pass freely therebetween, the thinner matrices of corresponding characters in passing through the same channels would be allowed to tilt at such an angle that their projecting ears would fail to properly engage the flanges b and likely become lodged beneath them so as to cause a piling up of succeeding matrices. These difficulties according to the present invention are overcome and the magazine entrance adapted to all fonts by adjusting certain of the leaf sections B^2 in relation to the partitions B^1 to which they have heretofore been fastened, and by regulating the adjustments so that the width of the respective channels will be varied according to the thickness of the corresponding characters of the particular font selected.

As best shown in Figs. 5, 6 and 7, the leaf sections to be adjusted and which occupy the channels M, W, V and B as indicated in Fig. 2, are hinged at their upper ends on axes disposed transversely of the entrance B and parallel to the delivery end thereof. These hinges, in the embodiment illustrated, are constituted by providing the leaf sections with trunnions b^2 which project from their opposite edges and are journaled in small bracket members B^3 riveted to the partitions B^1 and formed with inclined portions b^3 which fit against the side faces of the partitions and present smooth guiding surfaces to the descending matrices. The

lower ends of these hinged leaf sections B^2 are free to be adjusted relatively to the partitions so as to contract or expand the affected channels in the manner required. In the present instance, the adjustments of the said leaf sections are accomplished by means of a longitudinal strip D which is slidably mounted for endwise movement in the entrance supporting frame B^4 and arranged below the lower end portions of the partitions B^1 . A pin and slot connection D' located at opposite ends of the strip D restrains it against displacement and permits the endwise movement desired. At its lower edge, the strip D is provided with a series of notches d , one for each of the adjustable leaf sections B^2 , the latter being further formed with ears b^4 struck from their lower edges and turned down to engage within said notches. It will be noted (see Fig. 5) that these notches differ in width and that, when the strip D occupies the position shown, the leaf sections are pressed against the partitions to which they are attached through the engagement of the right side walls of the notches d with the ears b^4 . When the strip D is shifted to the dotted-line position, however, the several leaf sections, through the engagement of the left side walls of said notches with the ears b^4 , will be moved relatively different distances across their respective channels, the extent of movement of the individual leaf sections depending upon the lost motion allowed by the corresponding notches d . In other words, the relative width of these notches determines the extent of adjustment of the corresponding leaf sections B^2 . For example, it will be observed that the notch d for the W channel is much narrower than the corresponding notch for the V channel; consequently, the extent of adjustment of the leaf section for the former channel will be relatively greater and in proportion to the difference in the range of thickness of the two matrix characters.

In order that the adjustment of the leaf sections be effected with the desired degree of accuracy, there is also provided a cylindrical cam element E which is mounted to slide in a fixed bracket E^1 secured to the upper end of the magazine base frame C^1 . About midway of its length, the cam element E is provided with an operating pin E^2 which projects through a slot E^3 formed in the bracket E^1 and serves to prevent rotary displacement of said element. The upper end of the cam element E protrudes above the bracket E^1 and is formed with a series of graduated banking surfaces e and intervening bevels or cam surfaces e^1 arranged to engage one end of the adjusting strip D. A light pull spring D^2 anchored to the entrance supporting frame B^4 and connected to the strip D tends constantly to hold the

latter against one or another of the banking surfaces *e*. According to this arrangement, when it is desired to adjust the leaf sections *B*² to conform to a new matrix font, the cam 5 element is raised or lowered by means of the operating pin *E*² to bring the selected banking surface *e* opposite the ends of the strip *D*. If a thicker font is to be substituted for the one being used, the cam element *E* is 10 raised and, as the bevels or cam surfaces *e*¹ engage the strip *D*, the latter is forced thereby to the left against the tension of the spring *D*². The leaf sections *B*² are thus 15 swung in the same direction to increase the width of the respective channels, which is 20 determined by the banking surface selected and the width of the corresponding notches *d*. On the other hand, in changing from a thick to a thin font, the cam element is lowered and, by action of the spring *D*², the 25 operation is simply reversed to contract the channels.

The arrangement also enables the magazine entrance to be swung upwardly and downwardly about its pivotal axis *B*³ with the desired freedom for access to the magazine section *C*² or the magazine itself if the latter happens to be of full length. In this connection, it will be noted (see Fig. 2) that 30 one corner of the strip *D* is beveled off at *D*³ to avoid interference with the cam element *E* whenever the entrance is swung upwardly into its operative position.

While the adjustment of the leaf sections 35 might be effected by hand, it is further proposed in carrying out the invention to accomplish this automatically as the magazines are interchanged in operative position with one another. To this end, see Figs. 1, 40 3 and 4, the magazines are each provided with a font distinguishing plate *F* fastened to the magazine side bar *C*³ at the upper end thereof by clamping screws *F*¹ which engage slots *F*² formed in said plate. These slots 45 *F*² permit the plate *F* to be adjusted transversely of the magazine and, for reasons presently to appear, set at different operative levels according to the thickness of the matrix font contained at the time in the 50 magazine. Each font distinguishing plate *F* presents a beveled face *F*³ and a gage face *F*⁴, the latter being adapted to engage a pin *G*¹ projecting through one end of a pivoted rocking lever *G* when the magazine *C* occupies 55 its operative position. The lever *G* is connected at its opposite end to the pin *E*², before mentioned, which projects from the cam element *E*. A pull spring *G*², arranged between the lever *G* and the magazine base 60 frame *C*¹, acts through the former to hold the cam element *E* resiliently in its lowermost position. It will now be seen, according to the foregoing arrangement, that, as a magazine is pushed upwardly into operative 65 position on the base frame *C*¹, the cross pin

*G*¹ in the front end of the lever *G* will be cammed downwardly against the tension of the pull spring *G*² through its engagement with the beveled face *F*³ of the font distinguishing plate *F*, and as the magazine 70 reaches its operative position said pin will be located against the gage face *F*⁴. The lever *G* is in this way rocked about its pivotal axis and the cam element *E* caused to stand in one position or another according to the 75 level at which the distinguishing plate *F* and the gage face *F*⁵ happen to be disposed. The operation of the strip *D* and the adjustment of the leaf sections *B*² are thus effected in the manner before described.

As previously stated, the invention has been shown merely in preferred form and by way of example but obviously many changes and variations therein and in its mode of adaptation will readily suggest 80 themselves to those skilled in the art and still be comprised within its scope. It should therefore be understood that I do not wish to limit myself to any specific form or embodiment except in so far as such limitations 85 are specified in the following claims.

Having thus described my invention, its construction and mode of operation, what I claim and desire to secure by Letters Patent 90 of the United States is as follows:

1. In a typographical machine, the combination of a magazine entrance provided with a plurality of relatively fixed partitions dividing it into channels, with supplemental guiding elements adjustable relatively to the partitions to vary the widths of the channels to permit the passage therethrough of type or matrices of different thicknesses.

2. In a typographical machine, the combination of a magazine entrance provided with a plurality of partitions dividing it into channels, with leaf sections mounted on hinges and adjustable relatively to the partitions to vary the widths of the channels to permit the passage therethrough of type or matrices of different thicknesses.

3. In a typographical machine, the combination of a magazine entrance provided with a plurality of partitions dividing it into channels, with leaf sections hinged to the partitions and adjustable relatively thereto to vary the widths of the channels to permit the passage therethrough of type or matrices of different thicknesses.

4. In a typographical machine, the combination of a magazine entrance provided with a plurality of partitions dividing it into channels, with hinged leaf sections formed with flanges for guiding the matrices by their projecting ears, said leaf sections being adjustable to vary the widths of the channels to permit the passage therethrough of type or matrices of different thicknesses.

5. In a typographical machine, the combi-

- nation of a magazine entrance provided with a plurality of relatively fixed partitions dividing it into channels, with supplemental adjustable guiding elements arranged within the channels, and means for adjusting said elements to vary the widths of said channels to permit the passage therethrough of type or matrices of different thicknesses.
6. In a typographical machine, the combination of a magazine entrance provided with a plurality of partitions dividing it into channels, with hinged guiding elements arranged within the channels and formed with flanges for guiding the matrices by their projecting ears, and means for adjusting said elements to vary the widths of the channels to permit the passage therethrough of type or matrices of different thicknesses.
7. In a typographical machine, the combination of a magazine entrance provided with a plurality of partitions dividing it into channels of different widths, with auxiliary guiding elements arranged within the channels, said elements being capable of individual adjustment to vary the widths of the respective channels to permit the passage therethrough of type or matrices of different thicknesses.
8. In a typographical machine, the combination of a magazine entrance provided with a plurality of relatively fixed partitions dividing it into channels of different widths, with supplemental adjustable guiding elements arranged within the channels, and means for adjusting the elements to different relative extents according to the widths of the respective channels, for the purpose described.
9. In a typographical machine, the combination of a magazine entrance provided with a plurality of relatively fixed partitions dividing it into channels of different widths, with supplemental hinged guiding elements arranged within the channels, and unitary means for adjusting the individual elements relatively to the partitions according to the widths of the respective channels, for the purpose described.
10. In a typographical machine, the combination of a magazine entrance provided with a plurality of partitions dividing it into channels of different widths, with hinged guiding elements arranged within the channels, and a movable strip connected to said elements for adjusting them relatively to the partitions and according to the widths of the respective channels to permit the passage therethrough of type or matrices of different thicknesses.
11. In a typographical machine, the combination of a magazine entrance provided with a plurality of relatively fixed partitions dividing it into channels, with supplemental adjustable guiding elements arranged within the channels, and unitary means for

adjusting one or more of said elements as required to vary the widths of the corresponding channels to permit the passage therethrough of type or matrices of different thicknesses.

12. In a typographical machine adapted to be equipped with a plurality of magazines interchangeable in operative position with one another, the combination of a magazine entrance to cooperate with the magazine in operative position, said entrance being provided with a plurality of partitions dividing it into channels, a series of adjustable guiding elements mounted within the channels, and means for automatically adjusting said elements relatively to the partitions as the magazines are interchanged.

13. In a typographical machine, the combination of a plurality of magazines interchangeable in operative position with one another, a magazine entrance to cooperate with the magazine in operative position, said entrance being provided with a plurality of partitions dividing it into channels, a series of adjustable guiding elements mounted within the channels, and means controlled by the magazines as they are interchanged for automatically adjusting one or more of said elements relatively to the partitions to vary the widths of the corresponding channels to permit the passage therethrough of type or matrices of different thicknesses.

14. In a typographical machine, the combination of a plurality of magazines interchangeable in operative position with one another, a magazine entrance to cooperate with the magazine in operative position, said entrance being provided with a plurality of partitions dividing it into channels of different widths, and unitary means controlled by the magazines as they are interchanged for adjusting the individual elements relatively to the partitions and according to the widths of the respective channels, for the purpose described.

15. In a typographical machine, the combination of a plurality of magazines interchangeable in operative position with one another, a magazine entrance to cooperate with the magazine in operative position, said entrance being provided with a plurality of partitions dividing it into channels, a series of hinged leaf sections arranged within the channels, a movable strip connected to the leaf sections and operable to adjust them relatively to the partitions to vary the widths of the channels, and means controlled by the magazines as they are interchanged for operating said strip.

16. In a typographical machine adapted to be equipped with a plurality of magazines interchangeable in operative position with one another, the combination of a magazine entrance to cooperate with the magazine in

operative position, said entrance being provided with a plurality of partitions dividing it into channels, a series of hinged leaf sections arranged within the channels, and 5 automatic means for adjusting the individual leaf sections relatively to the partitions to vary the widths of the respective channels, said means comprising a strip opera-

tively connected to the leaf sections and projections on the magazines adapted to operate the strip as the magazines are interchanged. 10

In testimony whereof, I have affixed my signature hereto.

GEORGE A. DOXEY.
